US00D866585S

(12) **United States Design Patent** (10) Patent No.: **US D866,585 S**
 Burroughs et al. (45) Date of Patent: **** Nov. 12, 2019**

(54) **DISPLAY SCREEN WITH GRAPHICAL USER INTERFACE**

(71) Applicant: **NIKE, Inc.**, Beaverton, OR (US)

(72) Inventors: **Brandon S. Burroughs**, Portland, OR (US); **Michael B. Hailey**, Forest Grove, OR (US); **Kim Laama**, New York, NY (US); **Stefan Olander**, Portland, OR (US); **Michael J. Wood**, Portland, OR (US)

(73) Assignee: **NIKE, Inc.**, Beaverton, OR (US)

(**) Term: **15 Years**

(21) Appl. No.: **29/645,781**

(22) Filed: **Apr. 30, 2018**

(51) LOC (12) Cl. **14-04**

(52) U.S. Cl.

USPC **D14/486**
